UNITED STATES PATENT OFFICE.

HUGO WEDEKIND, OF NUERMBERG, GERMANY, ASSIGNOR TO EUGENE DIETZGEN COMPANY, OF CHICAGO, ILLINOIS, A CORPORATION OF ILLINOIS.

LETTERING INSTRUMENT.

Application filed August 31, 1925. Serial No. 53,753.

To all whom it may concern:

Be it known that I, HUGO WEDEKIND, a citizen of Germany, residing at Brunhildstr. 5-9, Nuremberg, Germany, have invented a certain new and useful Improvement in Lettering Instruments, of which the following is a specification.

My invention relates to pens, especially of the type commonly known as lettering pens, and the general object of the invention is to improve the construction by which the thickness of the line may be regulated. In carrying out my invention I provide a plurality of nibs (in the illustrated case, 15 four) and arrange them about a common longitudinal axis. I also provide means for controlling them simultaneously, the illustrated means being a tapered plunger and screw mechanism by which it may be 20 made to force them apart. The more specific objects of the invention are to provide a pen of this character and also to provide convenient means, and ones which are finely adjustable, for controlling the position of the 25 plunger and hence the spread of the nibs. Another object is to provide advantageous means by which ink may be supplied to the nib points.

I accomplish my objects by the construction illustrated in the accompanying drawings in which—

Figure 1 is a side elevation of the complete pen.

Figure 2 is an axial section of the pen 35 drawn to an increased scale.

Figure 3 is a cross section taken on the line 3—3 Fig. 2.

Figure 4 is a view of the nibs and a portion of the stem, the view looking toward the 40 right in Figure 2.

Figure 5 is a view looking directly at the point of the pen, that is, looking upward in Figure 2.

Like numerals denote like parts throughout the several views.

In the form selected to illustrate the invention the pen has a handle or body 10 which is longitudinally chambered at the center and at the lower end is internally threaded to screw into the threaded extension 12 of the stem 14 of the pen. The stem is also longitudinally chambered at the center and is internally threaded for a portion of its length. A plunger 16 fits slid- 55 ingly and rotatably within the stem and at

its lower end is tapered for the purpose hereinafter described.

At its mid portion the stem has an externally threaded section 18 which screws into the internally threaded extension 12 with the result that when the plunger is rotated the tapered lower end will be adjusted longitudinally of the instrument. At the upper end the plunger projects beyond the end of the handle 10 and is rotated by means of a cap 20 which is rigidly fastened to the plunger and has a knurled flange 32 to enable the user to rotate the stem readily. It is desirable to form an annular flange 24 at the lower end of the cap to fit loosely over the upper end of the handle and impart a finished appearance to the device.

Projecting from the lower end of the stem 14 are the nibs 26. As here illustrated these are four in number and slotted in such manner as to form four sections representing the four quarters of a cylinder. In other words, they are grouped symmetrically about a common longitudinal axis and have internal shoulders 28 adapted to be engaged by the tapered lower end of the plunger with the result that when the plunger is forced downward the nibs will be forced apart to increase the thickness of the line. For convenience it is desirable that the nibs 85 instead of being straight in line with the rest of the pen be curved as illustrated so that when the handle is held at a convenient slant the nib points will stand approximately vertical.

The two uppermost nibs have recesses 30 formed in their proximate surfaces somewhat above the nib points for containing the marking fluid which I will refer to generically as "ink".

According to the preferred construction the stem 14 is made of resilient metal and the nibs 26 are integral with it. This facilitates manufacture and gives a neat and workmanlike appearance to the article as a 100 whole. While the design may be varied the one illustrated is advantageous for the bend in the nibs occurs below the shoulders 28 and consequently the plunger is rectilinear and is thus simple to manufacture. In other 105 words, the curvature occurs beyond the point of coaction between the plunger and the point where the plunger engages the nibs.

The operation will now be readily understood. Ink placed within the recesses 30 110

will flow downward in the space between the nibs, being held there and in the recesses by capillary action. To increase the thickness of the line produced by the pen
5 the operator will rotate the cap 20 in the proper direction to lower the plunger 16. This forces the nibs outward, and as all four nibs are equally engaged and the arrangement is symmetrical with respect to
10 the central longitudinal axis, the movement of the nibs will be simultaneous and equalized. To decrease the width of the line which the pen will make the cap 20 is rotated in the reverse direction.
15 It will be noted that the pen is simple in construction and hence easy to manufacture. Furthermore if necessary for cleaning or other purposes the plunger may be entirely withdrawn by simply unscrewing it, and
20 lifting it out from the stem and handle. No tools of any kind will be required.

Having thus described my invention what I claim as new and desire to secure by Letters Patent is:

25 1. A pen having four resilient nibs grouped about a common axis and means for forcing them outward away from each other to increase the thickness of the line, said means including a longitudinally mov-
30 able element located in their midst.

2. A pen having a plurality of resilient

nibs grouped about a common axis, a tapered plunger located in their midst for forcing them apart, and threaded means for moving said plunger longitudinally for controlling the nibs. 35

3. A pen having a stem and four nibs extending therefrom and grouped about a common axis, and means for moving all of them simultaneously away from each other to 40 increase the thickness of the line, two of the nibs which normally lie uppermost having recesses in their proximate surfaces for containing the ink.

4. A pen having a plurality of resilient 45 nibs, a plunger located in their midst and movable longitudinally thereof to control their distance apart, and means located on the nibs chiefly below the plunger for supplying ink to the nibs. 50

5. A pen having a stem and four integral nibs spaced about a common axis and approximating the four quarters of a cylinder when viewed in cross section, a tapered plunger located in the midst of the nibs for forcing them apart when the plunger is moved downward, the plunger and stem having cooperating threads for controlling the position of the plunger longitudinally and means for rotating the plunger. 55

HUGO WEDEKIND.
